UNITED STATES PATENT OFFICE.

ALFRED SCHWARZ, OF UPPER MONTCLAIR, NEW JERSEY, ASSIGNOR TO COAL AND OIL PRODUCTS CORPORATION, A CORPORATION OF DELAWARE.

APPARATUS FOR CRACKING OIL.

Original application filed March 25, 1925, Serial No. 18,076. Divided and this application filed May 20, 1925. Serial No. 31,660.

This is a division of my application Serial No. 18,076 filed March 25, 1925.

This invention relates to an apparatus for what is known as oil cracking and gas making combined. Heretofore oil cracking has been usually carried on in stills of a tubular or shell type; and gas making has been largely a separate process, only small amounts of gas having been produced incident to oil cracking and as a matter of fact in oil cracking operations it was the aim heretofore to avoid the production of gas as much as possible. My apparatus however, is designed to combine both operations and utilize the waste heat from gas making for externally heating oil distilling apparatus, and also to utilize the heat of the gases to promote the cracking of oils by passing the same into direct contact with the carbon in the producer as well as joining in the vapors from the distilling apparatus, thus giving opportunities for heat exchange and chemical reactions as well.

The installation consists briefly of a gas producer which is operated not unlike an ordinary water gas producer, usually intermittent when water gas is to be made. The waste heat from the blowing period is conducted to any suitable oil still and the vapors from the oil still are passed to a fractionating tower where the hot gases from the producer join the latter, still hot enough to cause chemical interchange, at least in the lower section of said tower. Fractionating and refluxing devices are included in the installation thus gradually cracking and segregating the light products from such cracking operation and returning the medium products back into the cracking still circuits, while the tarry constituents are pumped from the bottom of the still into the producer and there cracked into carbon and light oils and gas, and the gas vapor mixture resulting from such operation after passing through the reflux tower being passed through a condenser where gas and liquids are separated.

The invention will be understood from the description in connection with the accompanying drawings, in which two arrangements of apparatus are shown. In the drawings, Fig. 1 is a somewhat diagrammatic view showing the arrangement of the apparatus, parts being shown in section, to

carry out the process and Fig. 2 is a similar view showing a modified arrangement of apparatus.

In the drawings, reference character 1 indicates a gas producer somewhat similar to those commonly used, the same being modified, however, so as to provide an upper still portion and adapt it especially for carrying out the present invention. The producer 1 has a main chamber 2 which may be lined with fire-brick, and a superimposed still chamber 3 having a waste heat duct 4 extending therefrom provided with a valve 5. The chamber 3 is closed at the top by a cover 6 which carries a perforated plate 6 to serve as an oil distributor as indicated below. A coal hopper 7 controlled by a valve 8 leads to the chamber 3 and the hopper 7 is supplied from a suitable source 9 that is provided with a valve 10 which may be opened and closed at will for feeding a charge of coal to the hopper 7.

The producer 1 is also provided with a grate 11 below which steam may be introduced into the producer through the inlet pipe 12, controlled by valves 36, from any convenient source. A valve controlled pipe 13, controlled by valve 38, leads from the producer 1 tangentially into a settling chamber 14 that is provided with an outlet pipe 15 controlled by the valve 16. A pipe 17 leads from upper portion of the settler 14 to a fractionating tower 18 which is provided with the usual shelves 19. This fractionating tower may also be filled, if desirable, with porous material such as coke, broken brick or the like. Reflux pipes, one of which is shown at 22, lead from the shelves to the lower end of the fractionating tower and a valved branch 24 may lead to a storage or supply tank. A pipe 25 leads from the fractionating tower 18 to a condenser 26 that may be cooled in any convenient manner. A pipe 28 leads from this condenser to a tank 29 that is provided with valved overflows or drains 30 and 31. A pipe 34 leads from the tank 29 through a pump 35 to a gas holder not shown. If desired two producers 1 may be connected to the tower 18, the same being operated alternately.

A branch pipe 39 provided with a valve 43 leads from the pipe 12 to the injector 40, having valve 44. The suction end of the injector 40 is connected by a pipe 41, con-

trolled by valve 45, to the supply tank 42 for oil that is to be cracked. A valved pipe 46 leads from the injector 40 to the cover cap 6. The oil from tank 42 may be forced 5 into the gas producer 1 by means of the injector 40 when gravity feed is not provided or a pump may feed the same. The discharge from pipe 15 of separator 14 and from the pipe 20 of the fractionating tower 10 18 may be introduced into the supply tank 42 if desired. A blower 47, provided with valve 49, may be used for starting the fire in the producer 1.

In the modification shown in Fig. 2 many 15 of the devices are identical with those already described in connection with Fig. 1 and such parts are indicated by the same reference character with the suffix "a". This arrangement differs in certain respects 20 from that shown in Fig. 1. The outlet pipe 4^a leads into a heating chamber 50 in which a still 53 is placed. This still is provided with tubes 51 which lead to a stack 52. A valved pipe 55 leads from the still 53 to the 25 valved pipe 17^a, that leads directly from the gas producer 1^a to the fractionating tower 18^a. One or more valved reflux pipes 22^a lead from the shelves 19^a to points below the liquid level in still 53. Two or more 30 gas producers 1^a may be connected to the still 53 and the fractionating tower 18^a and operated alternately. A pipe 41^a leads from near the bottom of the still 53 through a pump 57 to an injector 40^a. Steam may be 35 admitted to the injector 40^a through the pipe 39^a from any convenient source and a pipe 46^a leads from the injector to the cap 6^a of the gas producer.

The upper end of the tower 18 or 18^a 40 may be jacketed and the supply of water thereto may be controlled or regulated by means of valved pipes as shown at 60 (Fig. 2) so as to introduce steam or water around the upper portion thereof.

45 The process may be operated in two ways which may be termed "continuous" and "intermittent" respectively. In operating by the so-called continuous method, fire is started in the producer 1 on the grate 11, 50 coal or coke is then charged into the chamber 2 until it is filled nearly to below chamber #3. The blower 47 is started with the valve 5 open and the valves 8, 36, 38, 43, and 45 closed. The fire is blown until the 55 temperature near the top of the coke or coal reaches approximately 700 to 1000° F. When this temperature is reached the blowing is interrupted, the valve 38 is opened and the pump 35 is started. The vacuum 60 created by this pump will take in air through the blower 47, controlled by the valve 49, and superheated steam is admitted through valve 44 into the injector 40, while the oil is admitted from the tank 42 into the 65 injector 40 so that the atomized mixtures

are sprayed through the cap 6 into the chamber 2 where the coal in the upper part of the producer acts as a temporary retainer for the oil and the high temperature in this region will begin to crack the oil. The vapors therefrom will pass downwardly into a hotter region where more cracking will take place and carbon will be deposited, the vapors or gaseous products finally passing into the pipe 13 and through the settling 70 chamber 14 where suspended particles will be deposited and the vapors will then pass through a pipe 17 into the column 18 where the vapors are fractionated, the uncondensed portion passing through pipe 25 and condenser 26 wherefrom the uncondensed gases and the condensate pass into the receiving tank 29 where the water settles to the bottom and is withdrawn through the pipe 30 while the oil is withdrawn through the pipe 31, the fixed gases passing through the pipe 34 and pump 35 to a place of consumption or to a gas holder.

The reflux pipe 22 is arranged to lead the reflux from a plate 19 to the base of the tower where it can be introduced into the hotter portion of the tower through the pipe 23, or it may be withdrawn through the pipe 24. When introduced into the hotter portion of the fractionating tower 18, the condensate comes into contact with the hot gases from producer 1 whereby additional cracking takes place. More than one reflux line 22 may be used, leading from different plates 19. When a plurality of reflux lines are used to lead from separate plates 19, the condensates passed therethrough will be oils of different specific gravities and different qualities which may be subjected to further treatment in the tower 18, or they may be withdrawn from the system for other uses. The lighter oils will, of course, be drawn from the top shelves 19 of the fractionator and heavy oils from lower shelves. The heavy oils that may be withdrawn 105 through the pipe 20 may be passed through the system again by first introducing the same into the supply tank 42. In operating the process as above described, air is constantly taken into the system which is first caused to produce carbon dioxide in the lower part of the gas producer and, when the proper amount of air is introduced, this carbon dioxide is converted into carbon monoxide in upper layers of the incandescent coal or coke. Superheated steam is admitted through the pipe 12 and forms water gas in accordance with the well known reaction and the combined gases meet the oil vapors that pass downwardly through the upper portion of the producer and the mixture passes through the line 13 as above indicated. Reactions appear to take place between the gases and vapors, but on account of the fact that there are so many 110 115 120 125 130

different hydrocarbons present in the mineral oil vapors, the reactions of which are very complicated, it is not certain what the various chemical reactions are in the different reaction zones.

The following is given as an illustration of results that have actually been obtained with an installation of this character. With a gas producer 1, about 7' high and 14" in internal diameter and a fractionating tower 18, about 14' high and 12" in diameter arranged as illustrated in Fig. 1, I charged the producer with ordinary foundry coke and raised the temperature to about 800° F. and charged superheated steam through pipe 12 at a temperature of above 600° F. A vacuum pump of the eccentric piston type was set in operation as shown at 35 and a small amount of air was admitted through the valve 49. Petroleum oil having a boiling point such that about 12% could be distilled off between 500° F. and 600° F., the remainder boiling about 600° F., was introduced from the injector 40 through the spray box 6. This oil was the residue from a pressure cracking operation commonly called "pressure still tar" in the trade. The installation was operated for several hours and during that entire time gases obtained from the receiver 29 burned with a high calorific value and distillates collected from the pipe 31 contained 65% of the material that was distilled off between 120° F. and 437° F. and 60% of the remainder distilled below 600° F.

When operating the installation as just described, due to the continuous admission of air, there appears to be a considerable amount of hydrocarbon derivatives formed of the fatty acid series. And this constitutes an important factor in the process. Such fatty acids may be refined and used for many purposes, for example:—Manufacture of soap requires large quantities. If the process is operated with a view of making fatty acids as a by-product, the continuous admission of air is desirable. If however the process is operated more for the purpose of making motor fuel, a large amount of fatty acids in the distillate is not desirable. When it is desirable to avoid the production of fatty acids, the installation may be operated intermittently by first blowing air by means of the pump 47 through the gas producer 1 and permitting the products of combustion to pass out through the pipe 4 until the temperature has reached the proper point after which the air can be shut off and the oil sprayed in and the steam admitted until the temperature needs to be increased again. Another variation of my process is that I may mix the oil with ordinary live steam and pass both through a superheater and then introducing the mix-

ture through the distributor 6. When the installation is operated without an air supply during the time the oil is being admitted to the producer 1, the production of fatty acids is very nominal. During the time that air is being blown into the producer to raise the temperature of the carbon therein to incandescence, a certain amount of heat would be wasted but I utilize such heat by arranging the apparatus as indicated in Fig. 2. The products of combustion and blow gases pass in this arrangement of apparatus through the pipe 4^a into the fire box 50 along the under side of the still 53, which contains oil to be cracked, and these products then pass through the tubes 51 where they give up further heat to the oil and these gases finally pass out through the stack 52. Vapors from the oil in the still 53 pass through the pipe 55 to the tower 18^a. Reflux condensate passes through the pipe or pipes 22^a from the tower 18^a into the still below the liquid level therein. After the air has been blown into gas producer 1^a a sufficiently long time to bring the temperature to incandescence, the air is shut off and oil is passed by means of the pump 57 from the still or heater 53 through the injector 40^a and pipe 46^a into the spray box 6^a. Superheated steam may at the same time be admitted through the pipe 39^a and injector 40^a to the gas producer 1^a.

While I have described the operation as being conducted with the aid of steam which is preferably superheated, I do not limit myself to the use of steam as I may carry out the process without using steam by merely producing carbon monoxide gas and relying upon the reactions among the hydrocarbon vapors, the gas being used as a medium of heat transfer. The installation is adaptable to many grades of oil and the reactions will vary with the sort of hydrocarbons used. Not only very heavy oils and residues may be used as the stock to be cracked, but light oils such as kerosene and gas oil may also be treated by this process. At the same time other sorts of oils such as coke oven light oil, coal tar and the like may be introduced into the producer and may be subjected to the treatment above described.

While the most logical method of supplying heat to the oil vapors and water vapors for the purpose of inter-reaction is to abstract said heat from the gas producer, nothing herein-contained shall be construed to limit the scope of this invention by the additional application of external heat on any portion of the apparatus. While I primarily intend to extract the combustible products from the fixed gases, in some cases I may desire to conduct the mixed product to a burner or internal combustion engine and use all the products direct.

I claim:

1. In combination a gas producer, means for spraying oil onto the relatively cool bed of the gas producer, means for supplying steam to the incandescent bed of the gas producer, an oil still heated by the sensible heat of the waste gases of the gas producer, a filming apparatus for contacting the gas from the producer and the vapor from the oil still and for recondensing a portion of the vapors, and means for conducting the residual oil from the still to the relatively cool bed of the producer.
2. In combination a gas producer, means for spraying oil onto the relatively cool bed

of the gas producer, means for supplying steam to the incandescent bed of the gas producer, an oil still heated by the sensible heat of the waste gases of the gas producer, a filming apparatus for contacting the gas from the producer and the vapors from the oil still, means for conducting the residual oil from the still to the relatively cool bed of the producer, a fractionating column for recondensing a portion of the vapors, and means for conducting the reflux from the fractionating column back to the still. 25

In testimony whereof I affix my signature.

ALFRED SCHWARZ.
